UNITED STATES PATENT OFFICE.

LESTER W. BOND, OF NEW YORK, N. Y., ASSIGNOR TO BERBECKER & ROWLAND MANUFACTURING COMPANY, OF WATERVILLE, CONNECTICUT, A CORPORATION OF CONNECTICUT.

EXTENSION-ROD.

1,201,799.

Specification of Letters Patent. Patented Oct. 17, 1916.

Application filed June 17, 1915. Serial No. 34,576.

To all whom it may concern:

Be it known that I, LESTER W. BOND, a citizen of the United States, and a resident of New York, borough of Manhattan, in the county of New York and State of New York, have made and invented certain new and useful Improvements in Extension-Rods, of which the following is a specification.

10 My invention relates to extension rods such as are used for the support of curtains, draperies, etc.; one object of the present invention being to construct the ends of the telescoping rods so that, although the rods 15 are of different sizes allowing them to telescope one within the other, they are adapted to engage and be supported by, brackets of uniform size, thus rendering the extension rod reversible, end for end, and eliminating the use of right and left brackets.

A further object is to accomplish the aforementioned end by flattening the extremity of the smaller rod of the telescoping pair, so that the major diameter of the 25 oval or ellipse as thus formed is the diameter of the end of the other rod, thus rendering the rod reversible, end for end, and allowing it to be secured to brackets of uniform size and without resorting to the use 30 of auxiliary sleeves or bushings.

A further object is to provide a novel bracket for use in connection with the curtain rod, as above outlined, which is simple in its construction, of a neat and sightly 35 appearance, and at the same time one that may be economically manufactured.

A further object is to provide a bracket with the outstanding attaching member formed from a single length of wire, which 40 is looped upon itself so that the bracket will possess a strength and rigidness far exceeding that ordinarily required, and with the attaching member so formed that a certain resiliency and spring will be incorporated therein, which will prevent the accidental detachment of the extension rod 45 therefrom.

Other objects and advantages will appear as the description proceeds; wherein it is to 50 be understood, that changes in the precise embodiment of the invention can be made within the scope of what is claimed, without departing from the spirit thereof.

The preferred embodiment of my inven-

tion is disclosed in the accompanying drawings, wherein:

Figure 1 is a view in top plan of an extension rod embodying the characteristic features of my invention. Fig. 2 is a view in longitudinal vertical section of one end of the extension rod, and illustrating, in detail, my novel supporting bracket therefor. Fig. 3 is a view similar to the above, illustrating the other and remote end of the extension rod. Fig. 4 is a view in section taken on the line 4—4 of Fig. 3. Fig. 5 is a view in section taken on the line 5—5 of Fig. 2. Fig. 6 is a similar view taken on the line 6—6 of Fig. 3. Fig. 7 is a view in perspective of my novel supporting bracket. Fig. 8 is a view in front elevation of the supporting base of the bracket. Fig. 9 is a detail view in elevation of the wire supporting member. Fig. 10 is a view in side elevation and partially in section of a modified form of bracket. Fig. 11 is a view in front elevation of the supporting base of the bracket, and Fig. 12 is a view of the wire loop, which is utilized in connection with the modified form of bracket. Fig. 13 is a view in perspective of a somewhat further modified form of bracket.

Referring specifically to the several views, the curtain or extension rod is formed with the telescopic rods 15—16, the rod 15 being the smaller and slidably fitting within the rod 16, both of which are provided with the right angle bends 17, so as to form the conventional "goose-neck" curtain rod.

The exposed extremity of the smaller rod 90 is flattened, as illustrated in Fig. 6, so that an oval or elliptical end 18 is formed, the major axis of which, is substantially equal to the diameter of the end 19 of the larger rod. A uniform size of bracket may accordingly be utilized, doing away with the use of two sizes of brackets for the support of each curtain rod and furthermore rendering the latter reversible.

The preferred form of bracket for use in connection with the extension rod, as above outlined, is illustrated in Figs. 2 to 9 inclusive, and is formed with the base 20, through which extends suitable openings 21 for the reception of holding screws or analogous means, whereby the bracket may be rigidly secured to a supporting structure. The base, which is preferably stamped from

sheet metal, is formed with the slightly raised center or bridged portion 22, and from which projects the outwardly extending hub or retaining member 23. As first formed, the hub constitutes an open-ended receptacle, in which is inserted a supporting member 24, the same being preferably formed from a single length of wire, looped upon itself at its middle, and which loop portion is reduced in size, by the action of suitable dies or analogous means, so that the supporting member is provided with the securing end 25, the terminal of which is marked or defined by the shoulders 26. These shoulders bear against the end walls of the hub or retaining member 23 and hold the two in proper position during the time the securing member is being permanently attached to the base and increasing the permanency of said attachment.

The supporting member which is preferably formed of a single length of wire accordingly includes spaced sides, resiliently held apart and with the outer extremities thereof inwardly curved so that the supporting member will be provided with a rounded outer end. By the action of suitable dies the side walls 27 of the retaining member are compressed against the sides of the fixed end 25 of the supporting member, resulting in the rigid connection of the two. This connection between the base and supporting member is further strengthened by the heads 28 formed by upsetting the loop portion of the supporting member which projects within the raised portion of the base, these heads bearing against the back of the base and preventing the separation of the base and supporting member. The separated sides of the supporting member 24 and their spaced ends embody a certain degree of resiliency so that after the extension rod has been secured to the supporting brackets it will be rigidly so held.

A somewhat modified form of bracket is disclosed in Figs. 10 to 12 inclusive, wherein the hub or retaining member 29 is formed with the outer and apertured wall 30. The supporting member 33 is U-shaped and the ends 32 thereof are passed through the apertures 31 in the end wall of the retaining member and are provided with the heads 36. The ends 32 of the supporting member are somewhat reduced in size so as to define the shoulders 26' which, in connection with the heads 36, bear against the inner and outer portions of the base, and rigidly connect and secure the supporting member thereto. The side walls of the retaining member 29 are compressed into engagement with the ends 32 of the supporting member and further aid in the securement between the two. In both types of brackets, as thus described, the outer and free extremity of the supporting member is of rounded contour, facilitat-

ing the securement of the extension rod upon the brackets, which, having once been so assembled, are forcibly locked against detachment.

The bracket illustrated in Fig. 13 is formed entirely of wire, rendering it extremely cheap to manufacture, and at the same time it is capable of performing efficient service. It is similar to the previously-described types of brackets, in that it includes a base 44 from which projects the wire supporting member 42. The supporting member is of loop-shape, and includes the spaced sides 41, with the restricted or bent extremities 43, which correspond to the shoulder-forming bends of the previously described supporting members. The base 44 includes the eyelets 45 which are adapted to receive suitable holding screws therethrough, whereby the bracket may be rigidly secured to a supporting structure. The base in this latter-mentioned type of bracket, and also the bases of the previously described brackets, are of greater length than breadth, so that the spaced sides of the supporting member will be ordinarily placed in vertical alinement, in which position they are adapted to withstand the greatest strains, as will be readily appreciated.

What I claim is:—

1. An article of the class described comprising interfitting telescopic rods with hollow ends, the smaller rod being provided with a non-circular end with the major axis thereof substantially equal to the diameter of the end of the larger rod.
2. An extension rod comprising telescopic rods, the smaller rod provided with an oval-shape end with the major axis thereof approximating the diameter of the end of the larger rod.
3. An article of the class described comprising a pair of circular telescopic rods with hollow ends, the extremity of the smaller rod provided with an oval-shape end with the major axis thereof approximating the diameter of the end of the larger rod.
4. An article of the class described comprising a pair of hollow circular telescopic rods, the extremity of the small rod provided with an oval-shape end with the major axis thereof approximating the diameter of the end of the larger rod.
5. An article of the class described comprising a pair of hollow circular telescopic rods, the extremity of the small rod provided with an oval-shape end with the major axis thereof approximating the diameter of the end of the larger rod, and brackets therefor including relatively wide and thin supporting members.
6. A bracket comprising a base with an outwardly extending hub, a supporting member having a shoulder adjacent to the one extremity thereof, said supporting mem-

ber fitting within said hub, with the said shoulder resting against the outer extremity thereof, said supporting member provided with a head bearing against the inner extremity of said hub.

5 7. A bracket comprising a base, a loop-shape supporting member extending through and secured thereto, said loop-shape member provided with a head bearing against the rear surface of said base.

10 8. A bracket comprising a base with a bridged portion, a loop-shape supporting member with the base thereof fitting within and secured to said bridged portion, said 15 loop-shaped member provided with a head housed within the bridged portion of said base preventing the separation of the loop-shaped member therefrom.

19 9. A bracket comprising a base with a bridged central portion, a hub carried thereby, and a supporting member fitting within said hub and provided with a head located

within the bridged portion of said base and bearing against the rear surface thereof, said supporting member provided with a 25 shoulder bearing against the outer extremity of said hub.

10 10. A bracket comprising a base, a hub carried thereby, a loop-shape supporting member with a connected portion thereof fitting within said hub and secured thereto, the outer and exposed extremities of said supporting member provided with spaced and disconnected ends.

15 11. A bracket comprising a base, and a 30 loop-shape supporting member formed of wire and including spaced sides with restricted inner extremities.

Signed at New York, borough of Manhattan, in the county of New York and 40 State of New York, this 16 day of June, A. D. 1915.

LESTER W. BOND.
